SHIP STABILIZER

James V. Giliberty, Hempstead, N. Y.

Application December 21, 1938, Serial No. 247,045

5 Claims. (Cl. 114—132)

(Granted under the act of March 3, 1883, as
amended April 30, 1928; 370 O. G. 757)

The present invention relates to ship stabilizers and submarine bow planes and it has particular relation to planes of the variable angle extensible and retractable type.

5 The principal object of this invention is the provision of a ship roll or pitch stabilizer of the movable plane type which may be moved between extended and retracted positions and its angle of attack varied by the rotation of the 10 shaft upon which the plane is mounted and without any rectilinear movement or the use of any hinge or knuckle connections.

Another object of the invention is the provision of a stabilizer of the character described 15 which is suitable for use on submarine vessels.

A further object of the invention is the provision of a stabilizing mechanism which is responsive automatically to the roll or pitch of the ship and which may at the same time be 20 controlled manually from the ship's bridge.

With these and other objects in view, as well 25 as other advantages that may be incident to the use of the improvements, the invention consists in the parts and combinations thereof herein-after set forth and claimed, with the understanding that the several necessary elements constituting the same may be varied in proportion and arrangement without departing from the 30 nature and scope of the invention, as defined in the appended claims.

In order to make the invention more clearly understood, there are shown in the accompanying drawings, means for carrying the invention into practical use, without limiting the improvements in their useful application to the particular construction, which, for the purpose of explanation, have been made the subject of illustration.

In the accompanying drawings:

40 Fig. 1 is a fragmentary, transverse sectional view through the hull of a ship showing the improved stabilizing plane in its extended position;

45 Fig. 2 is an enlarged transverse sectional view taken on line 2—2 of Fig. 1, certain parts of the control system being shown diagrammatically;

50 Figs. 3 to 6 are diagrammatic views of the plane operating mechanisms in different positions;

Fig. 7 is an elevational inboard view of the plane in its extended position;

Fig. 8 is a plan view of the structure shown in Fig. 7;

55 Fig. 9 is a longitudinal sectional view of an

hydraulic ram mechanism for actuating the plane;

Fig. 10 is a fragmentary transverse sectional view through the hull of a submarine vessel, the plane being shown in its inoperative position. 5

Fig. 11 is an inboard elevational view of the plane shown in Fig. 10;

Fig. 12 is a similar view of the plane in its neutral position; and 10

Fig. 13 is a view of the plane rotated through 10° from the position shown in Fig. 12.

Referring to the drawings, and particularly to Figs. 1 to 6 thereof, a roll or pitch stabilizing mechanism constructed in accordance with the present invention is shown as comprising a plane 10

10 of any preferred contour and balance which is secured by a frangible flanged coupling 11 to a shaft 12 extending through the hull 13 of a vessel. The shaft 12 is rotatably mounted in a bearing 14 secured in the hull 13 and its outer extremity adjacent to the coupling 11 extends at an angle to the axis of the major portion thereof so that the plane 10 will be disposed at a corresponding angle. The plane 10 is oscillated between an extended protected position 25 and a position within a chamber or housing 15 in the hull of the ship and behind the overlying skin 13a thereof, by hydraulic means including a piston vane 16 which is keyed to the inner end of the shaft 12 for oscillation within an arcuate or semi-circular chamber 17 provided in a housing 18 mounted in the hull 13. 30

The vane 16 is oscillated in the chamber 17 by fluid under pressure which is forced through

35 the system in the desired direction by a pressure pump 19 driven by an electric motor 20. The

direction of flow of the fluid motive medium is controlled by a hollow cylinder valve member

21 which is rotatably mounted in a valve casing

22 in circumferentially spaced relation thereto, 40

the space therebetween being divided by two diametrically disposed partitions 23 into an inlet

chamber 24 and an outlet chamber 25. The interior of the cylinder valve 21 is likewise divided

45 into two chambers 26 and 27 by a diametrically extending rotatable partition or follow-up valve

28 having a gear segment 29 fixed thereto exteriorly of the casing 22 for intermeshing en-

gagement with a gear 30 fixed to the shaft 11, the ratio between the segment 29 and gear 30 50

being one to one. Communication between the inlet and outlet chambers 24 and 25 and the

chambers 26 and 27 is at times established

through a pair of diametrically disposed ports 31

and 32 in the cylinder valve 21. Communicat-

55

tion is established between the inlet and outlet chambers 24 and 25 and opposite sides of the pump 19 through pipes 33 and 34. Also, communication is established between the chambers 5 26 and 27 and the chamber 17 on opposite sides of the piston vane 16 through ports 35 and 36 in the end wall of the valve casing 22 and pipes 37 and 38.

The cylinder valve 21 is rotated in order to control the direction of flow of fluid to and from the several chambers and the direction and degree of movement of the piston vane 16 and stabilizing plane 10, by means of a three ring solenoid 39, one ring of which is stationary and provided with 10 a pair of oppositely disposed "housing" poles 40 and a pair of "neutral" poles 41 and the second and third rings of which are rotatable and provided with a pair of "incline" poles 42 and a pair of "decline" poles 43, respectively. Cooperating 15 with these poles is a single laminated armature 44 which is mounted on a shaft 45, to one end of which a segmental rack 46 is fixed for intermeshing engagement with a gear 47 fixed to the cylinder valve 21. The poles of these ring solenoids 20 may be selectively energized in order to rotate automatically the armature 44, segmental rack 46, gear 47 and cylinder valve 21, by means of a pilot control gyro indicated generally at 48 (Fig. 2).

30. This pilot control gyro is of commercial design and includes a frame 50 which is fixed to the ship so as to tilt with the roll thereof, and a rotor which is mounted in a casing 51 for rotation about a horizontal axis. The casing 51 of the 35 rotor is provided with a contact finger 52 engageable with an "incline" contact 53, a "neutral" contact 54 and a "decline" contact 55, all fixed to the frame 50 but insulated therefrom.

When it is desired to place the stabilizing mechanism under the automatic control of the pilot control gyro, a switch arm 56 is moved to a position in which it closes a contact 56^a. Assuming that the ship, at the moment, is on an even keel, a circuit will thereby be established from the ship's 40 electrical supply, through a wire 57, switch arm 56, wire 58, frame 50 and casing 51 of pilot gyro 48, contact finger 52, "neutral" contact 54, wire 59, windings of "neutral" poles 41 of the ring solenoid 39, and wires 60 and 61 back to source.

50. The energizing of these poles will cause the armature 44 to swing to the vertical position shown in Figs. 2 and 3 and, through the medium of the segmental rack 46 and gear 47, to rotate the cylinder valve 21 to a position in which the ports 55 31 and 32 communicate with the chambers 26 and 27 respectively, on opposite sides of the follow-up valve 28. This will permit fluid under pressure to flow from the inlet chamber 24 through port 32, chamber 26, port 35, and pipe 60 37 into right-hand side of the chamber 17, thus forcing the piston vane 16 in a counter-clockwise direction until the follow-up valve 28 rotating with the vane 16 but in an opposite direction, closes the ports 31 and 32, thus arresting the 65 motion of the ports in the "neutral" position shown in Fig. 3 in which the stabilizing plane 10 occupies a similar position. During this movement of the parts the fluid in the chamber 17 in front of the vane 16 is displaced therefrom 70 through the pipe 38, port 36, chamber 27, port 32, chamber 25 and pipe 34 back to the inlet side of the pump 19.

If, now, the ship should roll to starboard the frame 50 of the pilot gyro, moving with the 75 ship, will cause the contact finger 52 to leave the

contact 54, interrupting the circuit just traced, and engage the "incline" contact 53, thereby establishing a circuit through wire 62, windings of the "incline" poles 42 of the ring solenoid 39 and wires 63 and 61 back to source. The energizing 5 of these poles will swing the armature 44 in a counter-clockwise direction and rotate the cylinder valve 21 in a clockwise direction so as to carry the ports 31 and 32 therein to the positions shown in Fig. 4. This will permit fluid under 10 pressure to flow from the inlet chamber 24, through the port 31 into the chamber 26 at the right of the follow-up valve 28, and thence through the port 35 and pipe 37 into the chamber 17 on the right of the piston vane 16, thereby forcing the same in a counter-clockwise direction. This movement will continue until the 15 follow-up valve 28, now rotating in a clockwise direction, closes the ports 31 and 32, thus arresting the movement of the ports in the "incline" 20 positions shown in Fig. 4 in which the stabilizing plane 10 will occupy its maximum angle of attack.

In a like manner, if the ship should roll to the port side the frame 50 will tilt in a counter-clockwise direction breaking the circuit through contacts 52—53 and close contacts 52—55. This will establish a circuit through wire 64, windings of "decline" poles 43 of solenoid 39 and wires 65 and 61 back to source. The energizing of 30 these poles will swing the armature 44 in a clockwise direction and rotate the sleeve valve 21 in a counter-clockwise direction so as to move the ports 31 and 32 to the positions shown in Fig. 5. This will permit fluid under pressure to 35 flow from the inlet chamber 24, through the port 31 and into the chamber 27 and thence through the port 36 and pipe 38 into the left-hand side of the chamber 17 so as to force the piston vane 16 in a clockwise direction to the position shown in 40 Fig. 5, at which time the partition 28, moving in a counter-clockwise direction, will close the ports 31 and 32 and cause the cessation of further movement with the stabilizing vane disposed at its maximum angle of decline. 45

If it is desired to dispense with the stabilizing vanes, the switch arm 56 is actuated to open the circuit through contact 56^a and to close a circuit through a contact 56^b, wire 65, windings of "housing" poles 40 and wire 61 back to source. 50 The energizing of these poles will swing the armature 44 in a clockwise direction, thus rotating the sleeve valve 21 in a counter-clockwise direction so as to carry the ports 31 and 32 to the position shown in Fig. 6. This will permit fluid under 55 pressure to flow from the inlet chamber 24 through the port 31 into the chamber 27 and thence through the port 36 and pipe 38 into the left-hand side of the chamber 17. This will force the piston vane 16 in a clockwise direction and 60 swing the stabilizing plane 10 from an extended position to a retracted position within the housing 9 at which the time motion of the parts will be arrested by the follow-up valve 28, moving in a clockwise direction, closing the ports 31 and 32. 65

The working angle of the stabilizing vane may be controlled between the maximum angles of inclination and declination directly from the ship's bridge through the medium of a telemotor 66. This device is connected through linkage 70 mechanism 67 and gearing 68 with the movable rings of the solenoid 39 so that the "incline" poles 42 and "decline" poles 43 may be moved toward and from the neutral poles 41 the required distance and thus control the degree of rotation of 75

the armature 44 and sleeve valve 21 in opposite directions. The stabilizing planes 10 may thus be adjusted to the most efficient angle and in accordance with the roll of the ship. It will be understood that a stabilizing plane, such as that hereinabove described, is also provided on the port side of the ship but will rotate in an opposite direction from that on the starboard side so that when the plane on one side of the ship inclines the plane on the opposite side will decline. It will also be understood that when the invention hereinbefore described is employed in connection with submarine bow planes, the planes will incline and decline together.

15 In Fig. 9 there is shown another type of fluid pressure device for oscillating the shaft 12 and stabilizing plane 10 instead of the cylinder and oscillating vane hereinbefore described. This device comprises a pair of opposed cylinders 70 and 20 71 having rams 72 and 73 mounted for reciprocation therein. These rams are connected for movement in unison by means of a rack 74 which meshes with a segmented gear 75 fixed to the shaft 12. Fluid under pressure is at times admitted into one of these cylinders and permitted to escape from the other, through ports 76 and 77 adapted to be communicably connected with the pipes 37 and 38 which lead to the cylinder valve casing 22.

30 In Figs. 10 to 13 there is illustrated another type of plane particularly adapted for use with submarine vessels for submerging and raising purposes and comprising a plane 78 which is secured by means of a flanged coupling 79 to a 35 shaft 80 extending through the hull 81 of the vessel. The shaft 80 is rotatably mounted in a bearing 82 secured within the hull and its outer extremity adjacent to the coupling 79 extends at an angle to the axis of the major portion thereof 40 so that the plane 78 extends at a corresponding angle thereto, as in the structure first described. The shaft 80 is oscillated so as to swing the plane 78 between an extended position and a retracted vertical position alongside the conning tower of 45 the vessel by mechanism including a spur gear 83 which is keyed to the inner end of the shaft 80 for intermeshing engagement with a pinion 84. This pinion is fixed to a stub shaft 85 journalled in bearings 86 carried by a housing 87 and is 50 driven by a worm gear 88 fixed thereto and in turn driven by a worm 89 keyed to a shaft 90. This shaft is also journalled in the housing 87 and is rotated in any preferred manner, such as by an electric motor 91. A similar mechanism 55 for operating the plane on the opposite side of the vessel is also driven by the worm 89, the worm gears 88 being angularly arranged to permit the intermeshing of both gears with the worm. In this construction both planes incline and decline 60 together.

It will be understood that the above description and accompanying drawings comprehend only the general and preferred embodiment of the invention, and that various other changes in the construction, proportion and arrangement of the parts may be made by those skilled in the art without departing from the nature and scope of the invention as defined in the appended claims.

70 The invention described herein may be manufactured and/or used by or for the Government of the United States of America for governmental purposes without the payment of any royalties thereon or therefor.

I claim:

75 1. Stabilizing apparatus for ships comprising a

shaft rotatably mounted in and projecting through the hull of the ship, a vane carried by the outboard end of said shaft and extending at an angle to the axis of rotation thereof for swinging movement between an extended roll damping position and a retracted position substantially parallel to the side of the hull, hydraulic means for rotating said shaft, cylinder valve means for controlling the operation of said hydraulic means, means for operating said valve means, means responsive to the roll of the ship for controlling the operation of said valve operating means, and a second valve means actuated by said shaft for controlling the range of movement of said cylinder valve means.

2. Stabilizing apparatus for ships comprising a shaft rotatably mounted in and projecting through the hull of the ship, said hull including an outer skin, a plane carried by the outboard end of said shaft and extending at an angle to the axis of rotation thereof for swinging movement between an extended roll damping position and a retracted position substantially parallel to the side of the hull, said hull being formed to provide a recessed portion and a portion of said outer skin overlapping the recessed portion thereby substantially enclosing the same, and hydraulic means for rotating said shaft to swing said plane to a retracted position within said recessed portion and within the outline of and protected by said skin.

3. Stabilizing apparatus for ships comprising a shaft rotatably mounted in and projecting through the hull of the ship, a plane carried by the outboard end of said shaft and extending at an angle to the axis of rotation thereof for swinging movement between an extended roll damping position and a retracted position substantially parallel to the side of the hull, hydraulic means for rotating said shaft, cylinder valve means for controlling the operation of said hydraulic means, means for operating said valve means, means responsive to the pitch of the ship for controlling the operation of said valve operating means and a second valve means actuated by said shaft for controlling the operation of said cylinder valve means.

4. Submarine submerging and raising apparatus comprising a pair of shafts disposed one on each side of the bow of the vessel and rotatable in and projecting through the hull thereof, said hull including an outer skin, a plane carried by the outboard end of each of said shafts and extending at an angle to the axis of rotation thereof, said hull being formed to provide a recessed portion on each side of the bow thereof and a portion of said outer skin overlapping the recessed portion, thereby substantially enclosing the same, and means for rotating said shafts in the same direction simultaneously to swing said planes between extended planing positions and protected positions within said recessed portions back of the overlapping portions of the skin and for varying the angle of said planes when in their extended positions between declined submerging 65 positions and inclined raising positions.

5. Submarine submerging and raising apparatus comprising a pair of shafts disposed one on each side of the bow of the vessel and rotatable in and projecting through the hull thereof, said hull including an outer skin, a plane carried by the outboard end of each of said shafts and extending at an angle to the axis of rotation thereof, said hull being formed to provide a recessed portion on each side of the bow thereof 70

and a portion of said outer skin overlapping the recessed portion thereby substantially enclosing the same, and means for rotating said shafts in the same direction simultaneously to swing said planes in a conical path between extended planing positions and protected positions within said

recessed portions back of the overlapping portions of the skin and for varying the angle of said planes when in their extended positions between declined submerging positions and inclined raising positions.

JAMES V. GILIBERTY.
